UNITED STATES PATENT OFFICE.

ERNEST H. HORN, OF WATERBURY, CONNECTICUT, ASSIGNOR TO WATERBURY CLOCK CO., OF WATERBURY, CONNECTICUT, A CORPORATION.

MAINSPRING ARBOR FOR TIMEPIECES.

Application filed May 6, 1921. Serial No. 467,390.

To all whom it may concern:

Be it known that I, ERNEST H. HORN, a citizen of the United States, residing at Waterbury, in the county of New Haven 5 and State of Connecticut, have invented a new and useful Improvement in Mainspring Arbors for Timepieces; and I do hereby declare the following, when taken in connection with the accompanying drawings, and 10 the characters of reference marked thereon, to be a full, clear, and exact description of the same, and which said drawings constitute part of this application, and represent in—

15 Fig. 1 a perspective view of a main-spring arbor constructed in accordance with my invention.

Fig. 2 a plan view thereof with the inner end of the main-spring shown as applied to the annular notched rib of the arbor-hub.

20 Fig. 3 a detached plan view of the inner end of the main-spring showing its coupling-slot.

Fig. 4 a view of the arbor in end elevation 25 with the inner end of the main-spring in longitudinal section and shown in the position which the said end assumes when the spring is unwound, at which time the end of the spring engages with the safety-abutment of the arbor.

Fig. 5 a corresponding view showing the spring as wound and its inner end as engaged with the draft-abutment of the arbor.

Fig. 6 a sectional view on the line 6—6 of 35 Fig. 2.

My invention relates to an improved main-spring arbor for time-pieces, the object being to produce, at a low cost for manufacture, a simple and reliable arbor 40 constructed to provide not only an improved integral draft-abutment but also a safety-abutment arranged to prevent the spring from disengaging itself from the arbor when the spring is unwound.

45 With these ends in view, my invention consists in a main-spring arbor for time-pieces characterized by an annular rib transversely notched to produce, at one operation, a draft-abutment engaged by the inner end of the spring when the same is wound and an opposed safety-abutment positioned to be engaged by the extreme inner end of the spring when the same is unwound.

50 My invention further consists in a main-

spring arbor for time-pieces having certain 55 details of construction as will be hereinafter described and pointed out in the claim.

In carrying out my invention, as herein shown, I employ a main-spring arbor 6, having trunnions 7 and 8, a faced-off coupling-shoulder 9 and a hub 10 of approved construction. The hub 10, which slightly exceeds the width of the main-spring 11, is formed with a centrally-arranged, integral, annular rib 12, which, by a single milling 60 operation, is transversely cut through to form a segmental notch 13, the bottom of which coincides in curvature with the periphery of the hub. The cutting of the notch 13 results in the production of what, 65 for convenience, I shall call a draft-abutment 14 and a corresponding safety-abutment 15, these abutments facing each other and being tangential to the periphery of the hub and, therefore, hook-like in their 70 relations to the ends of the coupling-slot 16 in the inner end of the spring 11, in which the said slot, (which is a trifle wider than the width of the rib 12, as shown in Figure 2,) is placed with regard to the extreme end 75 of the spring, so as to produce a transverse tie-piece 17, narrower than the length of the said notch. When the spring is applied to the arbor, the tie-piece 17 enters the notch 13, as shown in Figures 2, 4 and 5. Then, 80 when the spring is placed under tension, the forward edge 18 of the tie-piece is engaged with the draft-abutment 14, as shown in Figure 5. Now, in the event of an excessive 85 unwinding of the spring, the inner end thereof is driven back in the notch 13, at which time the outer edge 19 of the tie-piece is crowded against the safety-abutment 15 and the spring prevented from disengaging 90 itself from the arbor, which is, in arbors as ordinarily constructed, a frequent 95 source of annoyance, calling for a considerable expenditure of time on the part of jewelers and watchmakers doing repairing and cleaning operations.

100 My improved arbor is easy and cheap to produce, since the draft- and safety-abutments of its annular rib are produced by a single milling operation, which is much cheaper than upsetting the metal to form an 105 integral hook and also much cheaper than to insert a separate pin to form a draft-hook, to say nothing of the advantage se-

cured, under my invention, by the concurrent production of a safety-abutment, as described.

I claim:

5 A main-spring arbor for time-pieces, the said arbor having a hub formed with a centrally located, integral, annular rib provided with a transverse segmental notch, the end walls of which are opposed to each other and respectively constitute draft- and

safety-abutments, and the floor of which conforms in curvature to the curvature of the said hub.

In testimony whereof, I have signed this specification in the presence of two sub- 15 scribing witnesses.

ERNEST H. HORN.
